UNITED STATES PATENT OFFICE.

WILLIAM B. GILES, OF PARK PLACE, TEXAS.

SAW FOR CUTTING PAPER ROLLS.

Application filed October 30, 1922, Serial No. 597,730. Renewed March 14, 1925.

To all whom it may concern:

Be it known that I, WILLIAM B. GILES, citizen of the United States, residing at Park Place, in the county of Harris and 5 State of Texas, have invented certain new and useful Improvements in Saws for Cutting Paper Rolls, of which the following is a specification.

This invention relates to new and useful 10 improvements in a saw for cutting paper rolls.

One object of the invention is to provide a saw of the character described whereby rolls of paper may be cut into sections of 15 any desired length.

Another object of the invention is to provide a device of the character described whereby the roll of paper may be slowly turned automatically and gradually fed to 20 the saw manually.

A further feature of the invention resides in the provision of a device of the character described so constructed that the roll to be cut may be easily mounted for the application 25 of the saw thereto, as well as easily adjusted on its mounting.

A still further feature of the invention resides in the provision of a simple and efficient paper roll saw which may be cheaply 30 and easily constructed and readily kept in condition for efficient use.

With the above and other objects in view the invention has particular relation to certain novel features of construction, operation 35 and arrangement of parts, an example of which is given in this specification and illustrated in the accompanying drawings, wherein:—

Figure 1 shows a side view of the device 40 partly in section.

Figure 2 shows an end view thereof partly in section, on the line 2—2 of Figure 1.

Figure 3 shows an end view of the shaft 45 for carrying the paper roll and the bearing therefor and,

Figure 4 shows a side view of the opposite end of said shaft mounted in its bearing.

In the drawings, the numeral 1 designates the frame work which preferably consists 50 of a table and supporting legs therefor. The numeral 2 designates a transverse drive shaft which is mounted in suitable bearings carried by the frame work and one end of which has the drive pulley 3 fixed thereon. 55 The other end of this shaft has the large

pulley 4 fixed on it which is alined with a similar pulley 5. This last mentioned pulley rotates on a suitable spindle 6 which is carried by the standards 7, upstanding from the frame work. A band saw 8 operates over the 60 pulleys 4 and 5. The frame work carries two transverse tracks 9, 9 mounted thereon and spaced apart, and whose facing sides have lengthwise grooves to receive the edges of the slide 10. This slide has a long angle 65 iron 11 bolted thereto and depending from which there is a lug 12. A crank 13 works in a bearing in said lug and is held against lengthwise movement relative thereto by means of the fixed collars 14, 14 fastened on 70 the shaft on opposite sides of the lug. The inner end of the crank is threaded through a tapped hole in the frame work and its outer end is formed into the usual handle 15 by means of which it may be turned. 75

By the operation of this crank the slide 10 may be adjusted toward and from the frame work. The numeral 16 designates the roll carrying shaft. One end of this shaft works between the fingers 17, 17 of the bearing 18 which is mounted on the corresponding end of the angle iron 11. Said end of this shaft has a deep annular groove 19 and there is an adjusting rod 20 which is threaded through the bearing 18 and which has a 80 fixed disc 21 thereon whose margin works in the groove 19. The shaft 20 has a grip handle 22 by means of which it may be turned and the shaft thus adjusted lengthwise. Provision is thus made for nice ad- 85 justment of the paper roll 23 relative to the saw. This roll is wound on a split mandrel 24 through which the shaft 16 extends, and the mandrel is tightened in the roll by expanding the same through the instru- 90

mentality of cone shaped collars 25 which are fitted on the shaft and whose small ends fit within the corresponding ends of the mandrel. These collars are keyed to the shaft by means of keys 26 providing for 100 their adjustment and the adjustment of the paper roll on said shaft. The other end of the shaft 16 is rotatable in a bearing member 27 which is mounted on the other end of the angle iron 11 and which is bifurcated forming the lugs 28, 28 spaced apart and between which the screw gear 29 works. The end of the shaft 16 works through bearings in the lugs 28, 28 and the gear 29 is splined thereon. The shaft bearings in said lugs are 110

somewhat larger than the shaft so that when it is desired to remove the roll of paper from the shaft 16 and place a new one thereon the opposite end of said shaft may be 5 lifted from the bearing 18 and the exchange made.

There is a transverse shaft 30 mounted at one end in the bearing 31 and at its other end in the bearing 27. This shaft is 10 driven from the shaft 2 through the belt 32 which operates over the pulleys 33, 33 mounted respectively on the shafts 2 and 30. There is a worm gear 34 splined on the shaft 30 and in mesh with the gear 29 through 15 which said last mentioned gear is driven in the direction indicated by the arrow in Figure 2. When the gear 34 is in driving relation with the gear 29 the former abuts against the bearing 27 and is held in said 20 driving relation. When it is desired to disconnect said gears the shaft 16 may be manually turned forwardly, in the direction indicated by the arrow in Figure 2 and this will operate to slide the gear 34 inwardly 25 on the shaft 30 and out of mesh with the gear 29.

In operation the saw is driven through the shaft 2 at the required rate of speed and the shaft 16 and the roll of paper mounted 30 thereon is automatically driven through the belt 32 at a slower rate of speed. The paper roll is adjusted to the desired place on the shaft 16 and is fed to the saw by slowly turning the crank 13 until the roll 35 is severed. The collars 25 are then released and the roll adjusted on the shaft 16 to the proper place for cutting another section. An accurate adjustment, however, of the roll is made through the adjusting rod 20 40 and the operation is repeated until the roll is cut into the required number of sections.

What I claim is:—

1. A device of the character described including a framework, band saw pulleys 45 mounted thereon, a band saw operating over said pulleys, means for driving one of said pulleys, an adjustable support carried by the framework and provided with end bearings, a shaft mounted in said bearings 50 means for adjustably mounting a paper roll on said shaft, means for manually adjusting said support toward and from the saw.

2. A device of the character described including a framework, band saw pulleys 55 mounted thereon, a band saw operating over said pulleys, means for driving one of said pulleys, an adjustable support carried by the framework and provided with end bearings, a shaft mounted in said bearings 60 means for adjustably mounting a paper roll on said shaft, means for manually adjusting said support toward and from the saw, and means for adjusting said shaft lengthwise in said bearings.

3. A device of the character described in-

cluding a framework, band saw pulleys mounted thereon, a band saw operating over said pulleys, means for driving one of said pulleys, an adjustable support carried by the framework and provided with end bearings, a shaft mounted in said bearings 70 expansible means on said shaft for carrying a paper roll, means for manually adjusting said support toward and from the saw and an operative connection through which said shaft may be rotated from said driving means.

4. A device of the character described including a framework, band saw pulleys mounted thereon, a band saw operating over 80 said pulleys, means for driving one of said pulleys, an adjustable support carried by the framework and provided with end bearings, a shaft mounted in said bearings an adjustable member on said shaft, for carrying a paper roll, means for manually adjusting said support toward and from the saw, means for adjusting said shaft lengthwise in said bearings and operative connections 85 between said shaft and driving means through which the former is driven from the latter.

5. A device of the character described including a framework, a band saw, pulleys over which said saw operates, means for driving one of said pulleys, an adjustable support mounted on the framework, end bearings carried by said support, a shaft mounted in said bearings, expansible means, adjustable on said shaft, for carrying a paper roll, a counter shaft geared to the roll carrying shaft, and driving the latter, and operatively connected with and driven by said driving means, means for manually moving said support and the paper roll carried thereby toward and from said saw.

6. A device of the character described including a framework, a band saw, pulleys over which said saw operates, means for driving one of said pulleys, an adjustable support mounted on the framework, end bearings carried by said support, a shaft mounted in said bearings provided to carry a paper roll, a counter shaft geared to the roll carrying shaft, and driving the latter, and operatively connected with and driven by said driving means, means for manually moving said support and the paper roll carried thereby toward and from said saw, and manually operable means for adjusting said roll carrying shaft, and the paper roll carried thereby, endwise with respect to said bearings.

7. A device of the character described including a framework, band saw pulleys mounted therein, a band saw operating over said pulleys, means for driving one of said pulleys, an adjustable support carried by the framework, and provided with end bearings, a shaft mounted in said bearings, 125

a paper roll carried on said shaft, means for manually adjusting said support toward and from the saw, a worm gear splined on said shaft, and bearing against one of said end bearings, said driving means embodying a gear which is in mesh with and drives said worm gear.

In testimony whereof I have signed my name to this specification in the presence of two subscribing witnesses.
